UNITED STATES PATENT OFFICE.

ALFRED E. HOLMES, OF CHICAGO, ILLINOIS, ASSIGNOR OF ONE-HALF TO WILLIAM H. PLUNKETT, OF CHICAGO, ILLINOIS.

LIQUID-DISPENSER.

1,208,784.

Specification of Letters Patent. Patented Dec. 19, 1916.

Application filed January 3, 1916. Serial No. 69,748.

To all whom it may concern:

Be it known that I, ALFRED E. HOLMES, a citizen of the United States, residing at Chicago, in the county of Cook and State of Illinois, have invented a certain new and useful Improvement in Liquid-Dispensers, of which the following is a specification.

My invention relates to liquid dispensers including such as are employed in toilet rooms for dispensing liquid soap.

The object of the invention is to provide a simple and sure-acting device which will be cheap to manufacture, easy to keep clean and which will always deliver a uniform amount of liquid if operated in a natural manner.

I accomplish my objects by the mechanism illustrated in the accompanying drawings, in which—

20 Figure 1 is a side elevation of a dispenser embodying my invention, the lower portion of the reservoir, cylinder and connected parts being in axial section. Fig. 2 shows the parts at the lower end of Fig. 1. In 25 this figure the plungers are shown in raised position. Fig. 3 is a plan section on the line 3—3, Fig. 1. Fig. 4 is a perspective of the plunger and stem.

Similar numerals refer to similar parts 30 throughout the several views.

In the form selected to illustrate the invention, the reservoir is constructed preferably of glass and supported upon any suitable type of bracket or standard 2. At the 35 top it is provided with a cap 3 of any suitable design through which the soap or other liquid may be introduced. At the bottom of the reservoir is a cylinder 5 having an annular flange 6 which abuts a washer 7 surrounding the lower mouth of the reservoir. Extending upward from the cylinder into the reservoir is a cylindrical chamber 8 which is externally threaded to take a nut 9 which screws down upon a washer 10 resting 40 upon the bottom of the reservoir. By tightening up this nut, the cylinder is rigidly supported upon the reservoir and leakage is prevented. Descending from the cylinder is an annular apron 12. This is of 45 larger diameter than the cylinder. By preference, the cylinder, apron, flange 6 and chamber 8 are all formed from a single piece 50 of metal.

The cylinder is of smaller diameter than 55 the chamber 8 and thus forms a valve seat

14 at the base of the chamber which co-operates with a valve 15, located at the upper end of the plunger 16. The valve 15 is of smaller diameter than chamber 8 and hence permits the liquid to pass between it and the 60 walls of the chamber. It is desirable to form laterally projecting fingers 18 at different points on the valve 15 which slide upon the internal walls of the chamber 8 and assist in guiding the plunger. They also scrape 65 the walls of the chamber and thus prevent the collection of verdigris, or of hardened soap.

The valve and plunger are normally held to their seat by a coiled spring 20, the lower 70 end whereof rests upon the top of the valve 15 and the upper end abuts a screw collar 21 which screws into the inside of the chamber 8 at the upper end thereof. A boss 19 rising from the valve 15 keeps the lower end of the 75 spring in place. The cylinder 5 is comparatively short; for example, in an ordinary dispenser for toilet soap it may be three-eighths of an inch long, more or less. By preference, the plunger 16 is of about the 80 same length as the cylinder and the parts are so proportioned that when the valve 15 is upon its seat as in Fig. 1 the lower end of the plunger will come on a level with the 85 lower end of the cylinder. Beneath the 90 plunger 16 is a second plunger 25 connected to it by the stem 26. The distance between the lower end of the upper plunger and the upper end of the lower plunger is slightly less than the length of the cylinder 5, the 95 result being that one plunger will always enter the cylinder before the other plunger has left it. This is true no matter in what direction the parts are traveling. Extending downward from the lower plunger is a 100 continuation 27 of the stem 26. By preference, the lower end of stem 27 is rounded to fit into the palm of the hand of the user and the parts are so designed that when the spring 20 is compressed and the plungers are as high as they will go, the top of the 105 lower plunger will be approximately flush with the top of the cylinder and the lower end of the stem will be always as high as the lower end of the apron.

In operation, when the reservoir has been filled and the parts are assembled, gravity assisted by the spring 20, will normally hold the valve 15 seated. Under these conditions the chamber 8 will be filled with liquid 110

and the valve will prevent the liquid from descending below the lower end of the chamber. When the operator wishes to obtain liquid, he presses upward on the stem 5 27. As the valve 15 rises, the liquid in the chamber 8 will pass by it, downward, but no liquid will flow into the cylinder until the lower end of the upper plunger has risen above the upper end of the cylinder. 10 When this occurs, the liquid will flow down into the cylinder, but by this time the lower end of the cylinder will be closed by the lower plunger and hence the liquid will be confined in the annular space between the 15 two plungers. After the space between the plungers has thus been filled, it is immaterial whether the plungers travel any farther or not, provided that the liquid has had time to fill the space. Consequently 20 the operator need not take pains to produce any specific amount of movement of the stem. As soon as the space between the two plungers has been filled and the operator lowers his hand, spring 20, acting in harmony 25 with gravity, will cause the plungers to descend until the lower plunger completely leaves the cylinder, whereupon the liquid is free to run down around the outside of the lower plunger between it and the 30 inside of the apron 12.

From the foregoing it will be evident that for every stroke of the plunger stem a definite quantity of liquid will be delivered provided the operator manipulates the parts in 35 a natural manner and gives the liquid time to flow down and fill the space between the two plungers. The liquid cannot run through, for the space between the plungers will never communicate with the space above 40 and below the cylinder; hence, my device constitutes a measuring dispenser in the sense that it will always deliver a fixed quantity of liquid. By preference, the two

plungers and their stems, together with the valve 15 and boss 19 are preferably turned from a single piece of metal, and hence it follows that, except for the reservoir, nuts and washers, the device is formed practically from only two pieces of metal. These pieces are of simple configuration and can be easily made and hence are easy to manufacture and easy to keep clean. Furthermore, there is, practically speaking, nothing to get out of order. There will be practically no possibility of soap caking on the inside of the mechanism for the plungers and valve are free to rotate and as the fingers 18 will thus slide along different parts of the inner wall of the chamber 8 during successive journeys they will tend to cover all parts of the surface in due time and hence keep the entire surface clean. 45 50 55 60

Having thus described my invention what I claim as new and desire to secure by Letters Patent, is:

In a liquid dispenser, a reservoir, a cylindrical chamber communicating therewith, a vertically arranged cylinder at the lower end of said chamber, said cylinder being of smaller diameter than the chamber, a valve seat formed at the junction of the chamber and cylinder, a stem, twin plungers secured to said stem one above the other, said plungers being closer together than the length of the cylinder, and a valve formed at the 75 upper end of the upper plunger, and adapted to seat upon said valve seat, said valve being of smaller diameter than the chamber, and a plurality of separate fingers projecting radially from said valve and making 80 sliding contact with the inner walls of the chamber, for guiding the plunger and scraping the walls of the chamber. 70 75 80

In witness whereof, I have hereunto subscribed my name.

ALFRED E. HOLMES.
